FABRICATED BRAKE BEAM

Edward J. Simanek, Chicago, Ill., assignor to
 American Steel Foundries, Chicago, Ill., a corporation of New Jersey

Application April 18, 1950, Serial No. 156,643

19 Claims. (Cl. 188—228.6)

1

This invention relates to brake beams and more particularly to a novel type of fabricated beam.

A general object of the invention is to provide a fabricated beam wherein the parts are arranged in a simple and efficient manner for economical manufacture and to withstand the severe abuse encountered in service.

A further object of the invention is to devise a novel fabricated truss wherein the tension member is afforded a single, effective and exceptionally rigid connection with the compression member.

A more specific object of the invention is to design a brake beam with a two strap tension member, one of the straps extending through the compression member and having its ends connected against the rear side of the compression member and the other of the straps being connected against the forward side of the compression member.

A further object of the invention is to provide a beam wherein the connection of the tension member with the compression member includes bending the extremities of one strap rearwardly around the ends of the compression member and bending the extremities of the other strap forwardly around the extremities of the one strap.

A still further object of the invention is to provide a truss structure of the type described wherein adjacent ends of the straps may be connected to the compression member by a single connection such as a rivet.

A different object of the invention is to provide a brake beam wherein the brake heads are removable from the truss without disassembling the truss.

The invention contemplates in one modification a novel pocket on the outboard side of the brake head for snugly confining the extremities of the tension member straps to resist the possibility of the extremities unbending from around the ends of the compression member.

The invention comprehends in an embodiment thereof an arrangement wherein one strap affords a seat for the brake head and the other strap is independent of the head.

These and other objects of the invention will become more apparent from the specification and the drawings, wherein:

Figure 1 is a top plan view of one form of the brake beam partly in horizontal section, the section being taken substantially on the line 1—1 of Figure 2;

Figure 2 is an end view partly in section, the section being taken substantially on the line 2—2 of Figure 1;

2

Figures 3 and 4 illustrate a modification of the invention, Figure 3 being a top plan view partly in horizontal section, the section being taken substantially on the line 3—3 of Figure 4; and

Figure 4 being an end view of Figure 3 partly in section, the section being taken substantially on the line 4—4 of Figure 3.

Describing the invention in detail and referring first to the embodiment shown in Figures 1 and 2, the brake beam comprises tension and compression members, generally designated 2 and 4.

The tension and compression members are connected intermediate their ends at the center of the beam by a strut, generally designated 6. The compression member is of channel form and comprises top and bottom rearwardly extending webs or flanges 8 and 10, and an intervening front wall 12. The front wall 12 is provided with openings 14, 14 adjacent each end through which ex-

20 tend the ends of an inner or rear strap 16 of the tension member. It will be noted that the tension member at opposite sides of the strut 6 is angled rearwardly toward the respective ends of the compression member. The end portions 18, 18 of the rear strap 16 are bent generally parallel to wall 12 and seat as at 20, 20 against the rear side of the front wall 12 of the compression member outboardly of the openings 14. The rear strap 16 seats on its forward side against the rear side of a front strap 22 of the tension member.

25 The front and rear straps are fitted within a socket 24 in the forward end of the fulcrum or strut 6. The rear end of the strut comprises a flange or base 26 secured by the plurality of rivets 28, 28 to the front wall 12 of the compression member.

Both straps 16 and 22, which constitute the tension member, extend the full length thereof and define bifurcated end portions. The strap 22 comprises end portions 30, 30 at each end bent

40 approximately parallel to the wall 12 and seated at their rear sides as at 32 against the forward face of the front wall 12 of the compression member. Adjacent portions 18 and 30 are connected against the web 12 in any suitable manner preferably as by rivet 34, the rivet passing through complementary aligned openings in the portions 18 and 32 and wall 12.

45 It will be noted that the tension member may be a single bar and may be bifurcated at its ends, however, the present structure is preferred, inasmuch as it is simple and possesses much greater strength.

The straps 16 and 22 are hooked around the ends of the wall 12, the strap 22 is bent rearwardly at its extremities to provide rearwardly

extending flanges 36, 36 in abutment at their inboard sides as at 38 with the adjacent outer edge of the wall 12. The outer extremities of the strap 16 are bent forwardly around the ends of the wall 12 to provide flanges 40 in abutment at their inboard sides as at 42 with the outboard sides of respective flanges 36. Thus the tension member, in addition to being connected at each end by the rivet 34 to the compression member, is also connected around the ends of the compression member. Inasmuch as the flanges 36 and 40 are very small, it will be readily understood that they are very difficult to unbend and serve as efficient anchors for the tension member, thus reducing shearing stresses on the rivets 34.

A brake head, generally indicated 44, is mounted at each end of the truss structure formed by the tension and compression member. Each brake head comprises a front wall 46 with a plurality of lugs 48, 48 thereon, adapted to afford a connection for an associated brake shoe, as will be readily understood by those skilled in the art. The head is provided with a hanger socket 50 intermediate its ends open in a throat 51 through the forward side of the head, the socket receiving a hanger 52 adapted to suspend the brake beam from an associated truck structure, as will be readily understood by those skilled in the art. The front wall 46 is connected at its rear side to the forward edges of top and bottom sections of a rear wall 54. The top and bottom sections 54 and the top and bottom portions of the front wall 46 are connected to an intermediate portion 56, within which is formed the above-mentioned socket 50. The intermediate portion 56 and the top and bottom rear walls 54, 54 are connected to top and bottom rearwardly extending, generally horizontal flanges 58 and 60. The flanges 58 and 60 and the rear side of the intermediate portion 56 of the head form a truss receiving cavity 62 within which extend the adjacent ends of the tension and compression members. The top web 58 of the head overlies the top web 8 of the compression member and is connected thereto by a plurality of rivets 64. The bottom flange 60 of the brake head underlies the bottom flange 10 of the compression member and is connected thereto by a series of rivets 66. It will be noted that the top and bottom flanges 58 and 60 of the brake head extend a considerable distance inboardly of the inboard side of the brake head and beyond the inboard extremity of the adjacent opening 14 in the front wall of the compression member in order to strengthen this area of the beam.

The rear side of the intermediate portion 56 of the brake head is provided with a recess 68 receiving the related end portion 30 of the strap 22 of the tension member. The front face of each portion 30 has a flat seat as at 70 against the rear side of the intermediate portion 56 of the related brake head within the recess 68 therein. It will be noted that the rivet head at the forward end of rivet 34 is countersunk within the portion 30 to provide a flat seat against portion 56. The head is also seated on the rear side of portion 56 as at 72, 72 along spaced areas above and below portion 30 against the forward face of wall 12 of the compression member. The brake head is provided at its inboard end with an abutment 74 extending inboardly from the inboard side thereof in order to provide a bearing or abutment for the tension member 4, said abutment affording a seat as at 76 at its

rear side against the forward side of the strap 22 adjacent its juncture with its end portion 30.

Referring now to the embodiment, shown in Figures 3 and 4, the brake beam comprises tension and compression members 100 and 102 interconnected intermediate their ends by a fulcrum or strut 104.

The compression member is of channel form and comprises top and bottom webs 106 and 108 extending forwardly from an intervening rear wall 110. The rear wall is provided adjacent each end thereof with an opening 112 through which extend the ends of a rear strap 114 of the tension member 100.

The strap 114 is provided with end portions 116 at each end, bent generally parallel to the rear wall 110 and seated on their forward faces as at 118 against the rear side of the wall 110 outboardly of the adjacent opening 112. The strap 114 is seated at its forward side against the rear side of a strap 120, said straps being fitted intermediate their ends within a socket 122 in the front end of a fulcrum 104. The rear end of the fulcrum extends between the webs 106 and 108 of the compression member and seats as at 124 against the forward face of wall 110 and is secured thereto as by rivets 126, 126.

The front strap 120 comprises end portions 128, 128, which are bent generally parallel to the wall 110 and seat on the rear sides against the forward side of wall 110 outboardly of the respective openings 112. A rivet 130 extends through adjacent portions 116 and 128 and wall 110, securing the same to each other. The tension member is additionally anchored to the compression member by being hooked around the ends of the compression member. This anchoring is afforded by bending the extremities of the strap 120 rearwardly to provide flanges 132 in abutment at their inboard sides as at 134 against the respective ends of the wall 110. The strap 114 is bent at its extremities around the ends of the compression member to provide forwardly extending flanges 136 which abut as at 138 at their inboard sides against the outboard sides of the respective flanges 132.

The arrangement of the tension and compression members constitutes a truss structure at each end of which is mounted a brake head, generally indicated 140. Each brake head comprises a front wall 142 which is broken apart intermediate its ends to provide a throat 144 which leads into a socket 146 formed within an intermediate portion 148 of the brake head. The socket receives a hanger 150 therein, the hanger being adapted to suspend the beam from an associated support structure such as a truck frame (not shown). The front wall is provided with a plurality of lugs 152 on the forward face thereof adapted to afford a usual seat and connection for associated brake shoe means (not shown) as will be readily understood by those skilled in the art. The front wall is connected on its rear side to the forward edges of top and bottom portions of a rear wall 154, said portions merging with the top and bottom sides of the intermediate portion 148 and with rearwardly extending top and bottom webs 156 and 158. The top and bottom webs and the rear side of the intermediate portion 148 form a truss receiving socket 160.

The top web 156 overlaps the top web 106 and the bottom web 158 underlaps the bottom web 108. The brake head is secured to the truss structure by means of a rivet 162 which passes

through the webs 156, 106 and 108, 158. The rivet also passes through a complementary opening in a spacer 164 which is snugly fitted between the top and bottom webs 106 and 108 of the compression member in order to prevent a collapse of these webs when the rivet is applied. The spacer 164 also provides a seat as at 166 for the tension member 100 on the forward face of strap 120 at the bend or inner end of the portion 128 of strap 120.

The brake head is provided on its inboard side with an inboardly extending abutment or lug 168, said abutment being disposed inboardly of the spacer 164 and extending between the webs 106 and 108 and affording a seat for the tension member as at 170 on the forward face of strap 120 at a point inboardly of the juncture with its end portion 128. The cavity 160 is closed at its outboard end by an outboard wall 172, said outboard wall being offset outboardly adjacent the rear of the head to provide an inboardly facing pocket 174, said pocket snugly receiving the outer extremities of the straps 114 and 120, namely the flanges 132 and 136, and providing an inboardly facing surface 176 tightly engaged with an outboardly facing surface on the outboard side of the adjacent flange 136. It will be readily understood that this type of connection and pocketing of the extremities of the tension member prevents the flanges 134 and 136 from unbending from around the end of the compression member when loads are applied to the tension member.

I claim:

1. In a brake beam, a truss structure comprising a channel compression member, having top and bottom webs and an intervening wall, said wall having openings adjacent the ends of said compression member, a tension member, a fulcrum interconnecting said members substantially centrally of the beam, said tension member comprising forward and rear straps extending longitudinally in adjacent relationship, the forward strap having end portions bent generally parallel to said wall and seated at their rear sides against the forward face of said wall outboardly of said openings and having their extremities bent rearwardly around respective ends of the wall, said rear strap extending adjacent each end through said openings and having end portions bent generally parallel to said wall and seated on their forward faces against the rear side of said wall outboardly of said openings and bent forwardly at their extremities around respective rearwardly bent extremities of said front strap, means interconnecting adjacent portions of the front and rear straps to said wall, a brake head at each end of said structure comprising a socket having a rearwardly facing surface in abutment with forwardly facing surfaces on said compression member above and below the adjacent end portions, each head having top and bottom webs connected to the top and bottom webs of said compression member.

2. A brake beam comprising tension and compression members and a fulcrum therebetween forming a truss structure, said compression member comprising spaced generally horizontal top and bottom webs and an intervening wall, said wall having openings therethrough adjacent its ends, said tension member having abutting front and rear straps, the rear strap having end portions extending through the openings and seated against the rear side of the wall outboardly of the openings, said front strap having end portions seated against the forward side of the wall.

outboardly of said openings, the end portions of one strap having segments bent around the ends of said wall and the end portions of the other strap having segments bent around the first-mentioned segments, means connecting adjacent portions of the front and rear straps to each other and to said wall of the compression member outboardly of said openings, brake head members mounted on the ends of said truss structure, and abutment means connected to at least one of the mentioned members disposed inboardly of said means and in abutment with the front face of the front strap of the tension member in an area adjacent the juncture of the end portions of the front strap with the remainder thereof.

3. In a brake beam, a truss structure comprising a channel compression member having a generally vertical wall, a tension member, a strut extending between said members intermediate their ends and having a socket at its forward end receiving said tension member and seated at its rear end against the forward face of said wall and connected thereto, said wall having openings therethrough adjacent each end of the beam, said tension member having a rear strap extending at its ends through the openings and against the rear side of the wall, said tension member having a forward strap abutting at its ends against the forward face of said wall, a rivet at each end of the compression member extending through adjacent portions of the straps and said wall, and a brake head on each end of said structure.

4. A brake beam, comprising a truss structure, having a U-section compression member with a generally vertical front wall and top and bottom webs extending rearwardly therefrom, said front wall having an opening adjacent each end, a tension member comprising a pair of straps extending alongside one another, one of the straps extending at its ends through the openings and having end portions extending outboardly of the openings against the rear side of said wall, the other strap extending at its ends against the forward side of the wall outboardly of said openings, and a rivet extending through adjacent ends of the straps and said front wall.

5. In a brake beam, a truss structure comprising tension and compression members, said compression member being of channel form and having a generally vertical web with openings therethrough adjacent the ends thereof receiving portions of the tension member therethrough, said tension member having other portions engaged with the forward side of the wall, and means connecting said first and second-mentioned portions to the rear and forward sides of said wall, respectively.

6. A brake beam, according to claim 5, comprising a brake head mounted on each end of the structure, each head having a pocket at its outboard side snugly receiving the adjacent ends of the first and second-mentioned portions therein.

7. In a brake beam, a truss structure comprising tension and compression members, said tension member having portions extending through said compression member adjacent its ends and said portions seating against the rear side of said compression member and having their extremities bent forwardly around the ends of the compression member, said tension member having other portions bent rearwardly around the ends of the compression member.

8. In a brake beam, a truss structure comprising a compression member, a tension mem-

ber having portions extending at the rear and front sides of said compression member adjacent each end thereof, one of the adjacent portions overlapping the other outboardly of the adjacent end of the compression member and all portions overlapping the adjacent ends of the compression member.

9. In a brake beam, a truss structure comprising tension and compression members and a fulcrum interconnecting said members at approximately the centers thereof, said compression member having spaced top and bottom webs and an intervening rear wall with an opening adjacent each end thereof, said tension member comprising front and rear straps, said rear strap having end portions extending through the openings and connected against the rear side of said wall, said front strap being connected to the front face of said wall, a brake head provided with a truss socket mounted on each end of said truss, said top and bottom webs being complementally received within said socket, said brake head having a lug in abutment with said front strap, a spacer disposed within said socket and in engagement with said top and bottom webs, and a rivet extending through said spacer, top and bottom webs, and said brake head to securely fasten each of said brake heads to said truss.

10. In a brake beam, a truss structure comprising tension and compression members and a fulcrum interconnecting said members medial the ends thereof, said compression member having a front wall with openings adjacent the ends thereof, said tension member having a portion extending through the openings and connected against the rear side of said wall, said tension member having another portion connected to the front face of said wall.

11. In a brake beam, a truss structure comprising tension and compression members and a fulcrum interconnecting said members medial the ends thereof, said compression member having a front wall with openings adjacent the ends thereof, said tension member having a portion extending through the openings and connected against the rear side of said wall, said tension member having another portion connected to the front face of said wall, said second mentioned portion being bent rearwardly at its extremities around the ends of the compression member to provide flanges bearing on their inboard sides against respective ends of said wall, said first mentioned portion being bent forwardly at its extremities around respective extremities of said second mentioned portion to provide flanges bearing at their inboard sides against the outboard sides of said flanges on the extremities of said second mentioned portion.

12. In a brake beam, a truss structure comprising tension and compression members and a fulcrum connecting said members medial the ends thereof, said compression member having a front wall with openings adjacent the ends thereof, said tension member having a portion extending through the openings and connected against the rear side of said wall, said tension member having another portion connected to the front face of said wall, said portions having extremities hooked around the ends of said compression member.

13. In a brake beam, a truss structure comprising tension and compression members and a fulcrum interconnecting said members medial the ends thereof, said compression member having a front wall with openings adjacent the ends

thereof, said tension member comprising front and rear straps, said rear strap having end portions extending through the openings and connected against the rear side of said wall, said front strap being connected to the front face of said wall.

14. In a brake beam, a truss structure comprising tension and compression members interconnected medial their ends by a strut, said compression member comprising spaced top and bottom webs and an intervening rear wall having openings adjacent its ends, said tension member comprising front and rear straps, said rear strap extending at its ends through said openings and connected against the back side of said rear wall and having its extremities bent forwardly around the extremities of said rear wall, said front strap having its ends connected against the front side of said rear wall and having its extremities bent rearwardly around the extremities of said rear wall, one of said strap extremities being bent around the other of said strap extremities, a brake head mounted on each end of said truss, said head having a truss socket for reception of the truss end, said top and bottom webs being complementally received within said socket, said brake head having a lug in abutment with said front strap, a spacer disposed within said socket and in engagement with the inner side surfaces of said top and bottom webs, and a rivet extending through said spacer, top and bottom webs and said brake head to securely mount the brake head to said truss.

15. In a brake beam, a truss structure comprising tension and compression members and a fulcrum interconnecting said members medial the ends thereof, said compression member having spaced top and bottom webs and an intervening wall, said wall having openings receiving the ends of the tension member therethrough, and connections between said ends of the tension member and the rear side of said wall, and a brake head mounted on the end of said structure and having a pocket on the outboard side thereof of receiving said tension member therein.

16. In a brake beam, a truss structure comprising tension and compression members, said compression member having openings adjacent its ends, said tension member having bifurcated ends embracing the ends of the compression member through said openings, and fastening means for securing said bifurcated ends to said compression member.

17. In a brake beam, a truss structure comprising tension and compression members and a fulcrum interconnecting said members medial the ends thereof, said compression member having openings adjacent its ends, said tension member extending at its ends through said openings against the back of said compression member and having its extremities bent forwardly around the extremities of said compression member, and a brake head mounted on each end of the structure, each head comprising an inboardly facing surface in abutment with an outboardly facing surface on the adjacent extremity to prevent the extremity from unbending from around said compression member.

18. A brake beam comprising a truss structure having tension and compression members, said compression member having openings adjacent its ends, said tension member having bifurcated ends embracing the ends of said compression member and having portions extending through said openings, fastening means for securing said

bifurcated end portions to said compression member, and a brake head mounted at each end of said truss structure, said brake head having a lug extending inboardly therefrom and bearing against said tension member.

19. A brake beam comprising tension and compression members, said tension member extending through the compression member adjacent its ends and against the front and the rear sides of said compression member and around the ends thereof. 10
